UNITED STATES PATENT OFFICE.

HARRY LANDSIEDEL, OF POPLAR BLUFF, MISSOURI, ASSIGNOR, BY MESNE ASSIGNMENTS, TO DALTON ADDING MACHINE COMPANY, OF CINCINNATI, OHIO, A CORPORATION OF OHIO.

RECORDING-MACHINE.

1,115,841.

Specification of Letters Patent.

Patented Nov. 3, 1914.

Application filed February 1, 1912. Serial No. 674,757.

To all whom it may concern:

Be it known that I, HARRY LANDSIEDEL, a citizen of the United States, residing at Poplar Bluff, county of Butler, and State 5 of Missouri, have invented a new and useful Recording-Machine, of which the following is a specification.

This invention relates to recording machines and, in a particular sense, to the 10 paper carriage of recording machines, and it consists of the novel construction, combination and arrangement of parts herein shown, described and claimed.

An object of the invention is to provide 15 a laterally-movable carriage, and a paper-roll support mounted on said carriage, with provisions for adjusting said support to receive rolls of different widths; said support is movably supported on the carriage 20 and may be adjusted or folded to a position flat upon the machine or carriage, in which it will occupy very little space, and will render the machine convenient for handling, as in moving the machine from place to 25 place.

Another object is to equip the carriage with adjustable retainers and rolls for the paper passing from the platen, with improved mountings for said rolls.

Other objects will appear from the following description, frequent reference being made to the accompanying drawings in which—

Figure 1 is a front elevation of a paper carriage containing my invention. Fig. 2 is a sectional view on the line 2—3 of Fig. 1, showing the adjustable roll pressing against the platen. Fig. 3 is a sectional view on the line 2—3 of Fig. 1, showing the roll adjusted and supported away from the platen. Fig. 4 is a sectional view on the line 4—4 of Fig. 1. Fig. 5 is a perspective view of a sleeve which cooperates with the feeding-out rolls to hold said rolls in or out 40 of operative position. Fig. 6 is a perspective view of one of the feeding-out rolls and its supporting bracket or yoke detached from the sleeve. Fig. 7 is a side elevation of a paper carriage equipped with my pres-

ent invention. Fig. 8 is a sectional view on 50 a line such as 8—8 of Fig. 1, showing the paper-roll support folded to lowered position. Fig. 9 is an enlarged perspective view of a part of the paper-roll support. Fig. 10 is a sectional view of the locking device which holds one of the arms of the paper-roll support. Fig. 11 is an enlarged 55 sectional view showing the latch device co-operating with the paper-roll support.

The platen 1 is mounted in a laterally- 60 movable carriage 2 operating upon a carriage support 3. A rod 4 is supported in a carriage above the platen and parallel therewith. A groove 5 is formed in the rod 4. Two collars 6 are slidably mounted 65 on the rod 4 and are prevented from turning thereon by screws 7, whose inner ends extend into the groove 5. Each of the collars 6 is embraced between the arms of a yoke or bracket 8 having enlarged holes 9 70 through which the rod 4 extends. Pins 10 on the ends of the collars 6 extend into the holes 9 and when the yokes or brackets 8 are raised notches 11 engage with the pins 10 and hold said yokes or brackets in their 75 raised adjustment. A roll 12 is supported on the front or lower end of each of the yokes or brackets 8 and said rolls constitute feed-rolls for the paper on the feeding-out side of the platen. A paper guide plate 80 13 is provided for each of the rollers 12 having up-turned arms 14 embracing the yokes or brackets 8, respectively. Small tongues 15 on the up-turned arms 14 extend into the groove 5 thereby preventing the guide 85 plates 13 from turning on the rod 4 and permitting lateral movement thereon when the feed rolls 12 are moved. The rolls 12 contact with the platen through openings 16 in the guide plates 13. A spring 17 (Fig. 4) 90 connects the bridge of each yoke or bracket 8 with a pin 18 on the under side of the collar 6, said springs actuating the rolls 12 into contact or engagement with the platen or the paper passing thereover. The bridge 95 of each of the yokes or brackets 8 has an upwardly curved finger piece 19 whereby the said yokes or brackets may be manipu-

lated to raise the rolls 12 out of contact with the platen or paper and also to permit lateral movement of the yokes or brackets and their associated parts on the rod 4. When raised to the desired position the notches 11, previously mentioned, engage with the pins 10 effectively to hold the parts in the adjustment shown in Fig. 3, which adjustment permits lateral movement of the parts on the rod 4.

The paper guide plates 13 are arcuate, conforming to the periphery or surface of the platen, and extend downwardly to a point near the upper edge of the paper-guide plate 20 extending from the feeding-side of the platen, so that the paper passing from said guide plate 20 will pass under the said plates 13 and be received and acted on by the rolls 12. A serrated plate 21 extends obliquely downwardly and rearwardly from the rod 4 and constitutes means for tearing or separating the paper ribbon or sheet passing from the paper feed rolls on the platen.

In the embodiment shown the carriage is provided with a paper table 22, having a graduated scale A arranged thereon. A member 23 rests against the paper table 22 and constitutes an adjustable guide or abutment whereby the paper may be adjusted in any desired position prior to producing records thereon, the scale A constituting means whereby the guide may be located in exactly the desired position. Said guide is movably mounted on the rod 4 and is provided with a locking-nut 24 whereby said guide may be firmly secured and held in any desired position.

A frame 25 is mounted upon the frame of the carriage 2 and is provided with bearings in which a rod 26 is journaled. An arm 27 is rigid upon one end of the rod 26 and a similarly shaped arm 28 is removably mounted upon the other end of said rod, being provided with a locking-nut 29^a, whereby said arm may be firmly held parallel with the arm 27 and prevented from accidental movement. The nut 29^a is preferably of the usual construction employed for the purpose of locking a collar or sleeve upon a rod or shaft. As usual, the nut is provided with an opening which is slightly eccentric, and is also provided with internal threads for a portion of its length only, 55 which threads are adapted to engage with external threads on the hub of the arm 28 as illustrated in Fig. 10. Since the opening through the nut is eccentric with respect to the opening of the hub of the arm 28 the said arm 28 will be clamped and rigidly held upon the rod 26 by the engagement of the nut upon the threaded portion of the hub of said arm, as usual in such devices.

A groove 29 is formed in the lower side of the rod 26. Each side of the frame 25 supports a housing 30 in each of which is a ball 31, arranged to engage in the groove 29 when the arms 27 and 28 are in their raised position, shown in Fig. 7. A spring 32 in each housing actuates the ball 31 therein, 65 said balls thereby constituting a yielding latch or lock which is effective to hold the paper-roll support, including the arms 27 and 28, in their operative adjustment under all ordinary requirements. The paper-roll 75 support, however, may be moved forwardly on to the paper carriage by force or power in excess of that required to draw the paper from the paper-roll, the latch balls 31 yielding to the pressure and permitting such 80 operation. The housing 30 has lips 33 which form a narrow opening and prevent removal of the balls 31 when the paper-roll support is removed from the frame 25, which may be accomplished by detaching 85 the arm 28 and withdrawing the rod 26. The entrance to each housing is closed by a plug 34 which may be removed whenever 90 desired for purposes of replacing the springs 32, etc.

The free end of each of the arms 27 and 28 is provided with a projection 35, said projections being arranged to engage in holes in the ends of a paper-spool 36 and thereby revolvably support said spool so that 95 the paper therefrom may be fed to the platen in whatever position said platen may be. A spring on the arm 27 may be provided so as to press against the end of the paper spool 36 and create the necessary resistance to prevent loose un-winding of the 100 paper.

It will be noted that the paper-roll support is mounted directly on, and therefore is laterally-movable with, the paper carriage. This permits the mounting of wide rolls of paper on the platen so that two or more parallel columns of items or other data may be recorded thereon, provision being made for supporting rolls of various 110 widths through adjustment of the arm 28 and movement of the rod 26 so as to position the roll on the center of the paper carriage.

My invention is especially adapted for 115 use upon the carriage of an adding machine or an adding and typewriting machine, and possesses superior advantages over any carriage in which the paper-roll is not supported and movable laterally by the carriage.

I do not restrict myself in the claims to identical features of construction and arrangement for it is apparent that there may be many mechanical departures and 125 variations from the arrangement shown and

described without departing from the spirit and scope of the invention.

Having described one embodiment of my invention what I claim and desire to secure 5 by Letters-Patent is:

1. In a recording machine, a platen, a rod supported parallel with said platen, a collar arranged to slide on said rod, latch pins rigid with said collar, a yoke or bracket 10 movable with said collar and having notches therein arranged to engage with said latch pins, a roller supported by said yoke and arranged to coöperate with the platen to feed paper, and a spring actuating said 15 yoke to press said roller against said platen or to hold said bracket in position with said notches engaging with said pins, as desired, substantially as specified.

2. In a recording machine, a platen, a rod supported parallel with said platen, a collar arranged to slide on said rod, means 20 preventing said collar from turning on said rod, a paper guide plate supported independently of and movable with said collar, a yoke or bracket pivotally supported independently of said guide plate and in connection with said collar, a roller supported by said yoke or bracket, and a spring effective 25 to hold said roller in contact with the platen, substantially as specified.

3. In a recording machine, a platen, a rod supported parallel with said platen, a paper guide plate movable on said rod, tongue and groove connection between said 35 guide plate and said rod, a bracket or yoke revolvable on said rod independently of said guide plate, a roller supported by said bracket or yoke, a spring effective to press said roller into contact with the surface of 40 the platen, and a handle whereby said bracket or yoke may be manipulated effectively to move said roller out of contact with said platen and to move said guide plate and said bracket and roller to different 45 adjustments on the rod, substantially as specified.

4. In a recording machine, a platen, a pair of arms, means for holding one of said arms positively in different adjustments 50 relative to the other arm, means for holding a roll of paper between said arms, means for holding said arms in different lateral positions relative to said platen whereby paper may be fed from a roll between said arms 55 to different selected parts of said platen, a paper table arranged to guide paper from a roll between said arms partially around said platen in the different lateral positions of said arms, a rod, guide plates on said 60 rod arranged to receive paper passing from said roll and passing from said paper table, and means for moving said guide plate laterally on said rod to conform to the dif-

ferent lateral positions of said arms and to the position of the paper passing from the 65 roll between said arms, substantially as specified.

5. In a recording machine, a laterally movable paper carriage, a platen in said carriage, a paper support on said carriage 70 and movable laterally to different operative positions relative to said carriage and relative to said platen, means for holding a roll of paper in said support in any position of said support, a paper table arranged to 75 guide paper from said roll partially around said platen in any position of said paper support, a rod in said carriage, brackets supported by said rod, rollers carried by said brackets and arranged to coöperate 80 with said platen to feed paper from said roll in any position of said support, means for moving said brackets laterally on said rod to coöperate with said platen in any position of said paper support, and a paper 85 knife carried by said rod and limiting movement of said guide plates, substantially as specified.

6. In a recording machine, the combination with a laterally movable paper carriage, and a support mounted on said carriage, of a rod mounted in and movable with respect to said support, an arm attached to said rod, a second arm attached to said rod, means 90 for binding said second arm in different adjustments with respect to said first-named arm, elements supported by said support and engaging said rod to hold said arms in an upright position and means for holding a roll of paper between said arms, substantially 95 as described.

7. In a paper carriage, a platen arranged to feed paper, a frame, arms supported by said frame, means for locking one of said arms in different adjustments with respect to the other arm, means for supporting a roll of paper between said arms, and a device effective to hold said arms in nearly a vertical adjustment and permitting said arms to be folded to inoperative position 105 when not in use, substantially as specified.

8. In a recording machine, a laterally movable paper carriage, a platen in said carriage, a frame on said carriage, paper supporting devices carried by said frame 110 and movable laterally to different operative positions relative to said carriage, means for supporting a roll of paper by said supporting devices, a paper table arranged to guide paper from said roll partially around said platen in any of the lateral positions of said supporting devices, a rod in said carriage, rollers supported by said rod and arranged to coöperate with said platen to feed paper 115 from said roll in any position of said supporting devices, means whereby said rollers 120

125

may be moved laterally to coöperate with said platen to feed paper from said roll in any position of said supporting devices, a guide supported by said rod and engaging with said paper table to guide the paper to the platen, and means for binding said guide in position on said rod to guide the paper from said supporting devices to said rollers in whatever position said supporting devices and said rollers may be coöperatively ad-

justed for feeding paper, substantially as described.

In witness whereof, I have signed this specification in the presence of two subscribing witnesses.

HARRY LANDSIEDEL.

Witnesses:

**SAM G. DORMAN,
B. C. HARRISON.**

It is hereby certified that the assignee in Letters Patent No. 1,115,841, granted November 3, 1914, upon the application of Harry Landsiedel, of Poplar Bluff, Missouri, for an improvement in "Recording-Machines," was erroneously described and specified as "Dalton Adding Machine Company," whereas said assignee should have been described and specified as *The Dalton Adding Machine Company*, as shown by the records of assignments in this office; and that the said Letters Patent should be read with this correction therein that the same may conform to the record of the case in the Patent Office.

Signed and sealed this 24th day of November, A. D., 1914.

[SEAL.]

R. F. WHITEHEAD,
Acting Commissioner of Patents.
